(57) **CLAIM**

The ornamental design for the flexible gusseted bag, as shown and described.

DESCRIPTION

FIG. 1 is an isometric view of the flexible gusseted bag including heat seals in accordance with my new design and shown in its unfilled (flattened) state and with heat seals of the bag shown by stippling;

FIG. 2 is a front elevation view of the flexible gusseted bag shown in FIG. 1;

FIG. 3 is a rear elevation view of the flexible gusseted bag shown in FIG. 1;

FIG. 4 is a right side elevation view of the flexible gusseted bag shown in FIG. 1;

FIG. 5 is a left side elevation view of the flexible gusseted bag handle shown in FIG. 1;

FIG. 6 is a top plan view of the flexible gusseted bag shown in FIG. 1;

FIG. 7 is a bottom plan view of the flexible gusseted bag shown in FIG. 1;

FIG. 8 is an isometric view of the flexible gusseted bag of FIG. 1, but with the bag shown in its filled state;

FIG. 9 is a front elevation view of the flexible gusseted bag shown in FIG. 9;

FIG. 10 is a rear elevation view of the flexible gusseted bag shown in FIG. 9;

FIG. 11 is a right side elevation view of the flexible gusseted bag shown in FIG. 9;

FIG. 12 is a left side elevation view of the flexible gusseted bag handle shown in FIG. 9;

FIG. 13 is a top plan view of the flexible gusseted bag shown in FIG. 9; and,

FIG. 14 is a bottom plan view of the flexible gusseted bag shown in FIG. 1.

The broken lines in the various figures are directed to unclaimed portions of the flexible gusseted bag and form no part of the claimed design.

1 Claim, 10 Drawing Sheets
